UNITED STATES PATENT OFFICE

140,119

DESIGN FOR A KNITTED SKIRT

Wally Johnson, Los Angeles, Calif.

Application June 27, 1944, Serial No. 114,210

Term of patent 14 years

(Cl. D3—26)

To all whom it may concern:

Be it known that I, Wally Johnson, a citizen of the United States, residing in the city of Los Angeles, county of Los Angeles, and State of California, have invented a new, original, and ornamental Design for a Knitted Skirt, of which the following is a specification, reference being had to the accompanying drawing, forming a part thereof.

Fig. 1 is a perspective view of the knitted skirt showing my new design, and Fig. 2 is an enlarged fragmentary view of the skirt shown in Fig. 1 illustrating the texture of the fabric in detail.

I claim:

The ornamental design for a knitted skirt, as shown and described.

WALLY JOHNSON,
